VANITY CASE

Filed Dec. 4, 1930

Inventor

Winfred T. Parkin
By Joseph A. Miller

Attorney

UNITED STATES PATENT OFFICE

WINFRED T. PARKIN, OF PROVIDENCE, RHODE ISLAND, ASSIGNOR TO THEODORE W. FOSTER & BRO. CO., OF PROVIDENCE, RHODE ISLAND

VANITY CASE

Application filed December 4, 1930. Serial No. 499,905.

This invention relates to vanity cases and pertains more particularly to the powder dispenser.

The primary object of the invention is to provide improved means for mounting the disk or valve which controls the outlet of the powder compartment, and more specifically aims to provide an integral construction of valve wherein resilient means are embodied for mounting the valve in position, or in other words to provide a one piece or integral spring plate or closure and mounting for the outlet of the powder compartment.

15 A further object of the invention is to provide means for mounting the valve or spring closure which eliminates the use of solder or other extraneous fastenings, and which more specifically resides in striking 20 out portions of the top of the powder compartment and in providing bendable projections on the spring supports for plate or closure that are extended through the struck out portions and clinched in position.

25 Still further, the invention aims to provide a top for the powder compartment which can be readily and easily removed and replaced in replenishing the supply of powder and more specifically to enable the top to be positioned at any point throughout its circumference.

In the drawings:—

Figure 1 is a top plan view of a vanity case embodying the present invention, the 35 parts being shown in open position;

Figure 2 is a section on line 2—2 of Figure 1;

Figure 3 is a bottom plan view of the invention applied in position on the removable 40 top of the powder compartment.

In proceeding in accordance with the present invention, 1 designates the body of the case which may be formed in any preferred manner and which has the usual top 45 2 hinged thereto at 3. A substantially cup shaped member 4 is positioned in the body 1 and has an outwardly extending rim 5 which latter underlies and is held in position by the inwardly extending circular lip or flange 50 6 of the body 1. The top of the powder com-

partment is composed of a circular ring like plate 7 formed of spring metal the central opening 8' of which forms the outlet of the powder compartment, the latter being formed by and between the parts 4 and 7. 55 The top 7 is formed with a depending flange which latter is provided with a depressed circular groove 10. The rim 5 is as shown in Figures 1 and 2 provided with inwardly struck teats 9 which latter are 60 adapted to engage in the circular groove 10. It will be understood that the material of which the top 7 is formed is preferably spring metal and consequently the flange of the top may be readily sprung into engagement with the teats 10 and may be easily disengaged therefrom by inserting a sharp edged instrument such as a knife or pin in the opening 11 provided for this purpose 65 in the rim 5 of the cup 4.

70 Referring now particularly to Figure 3 of the drawings, it will be seen that a valve or closure plate 12 is provided which latter underlies and normally closes the outlet 8 of the powder compartment. For the purpose 75 of resiliently mounting the valve or plate 12 in position, same is formed with a series of preferably three curved spring arms 13 which lie in spaced relation to the periphery of the plate and therebeyond, being connected thereto by radial arms 14. For the purpose of reinforcing and strengthening the arms 13 same are preferably formed with struck-out ribs 15 that follow the curvature of the arms and which in cross section are 80 shown in Figure 2. Each curved arm 13 has its outer end free and is formed with a projection 16 which latter is extended through an opening 17 resultant from downwardly struck parts 18 formed in the top 7 85 of the powder compartment. As shown clearly in figure 2, the projections 16 are bent to lie in the depressed parts 18 so as to be flush with the upper face of top 7. 90

95 From the foregoing it will be observed that the plate is provided with a three point spring mounting or suspension, the points being equi-distantly spaced circumferentially of the plate. It will further be observed that the use of soldering or rivets, or other 100

extraneous fastenings for the plate are all eliminated due to the clinching of the free ends of the arms to the top 7 of the powder compartment, and a structure is provided which not only is effective in use, but which is also reliable in operation and one in which the parts can be easily and quickly assembled.

It will further be seen that due to the 10 valve or closure being suspended from three equi-distant points, that same is uniformly supported so that upon depression, to release the powder, the plate or closure 12 will move in a plane substantially parallel to the 15 plane of the top 7.

Having thus described my invention what I claim as new and desire to secure by Letters Patent is:—

1. In a vanity case having a powder compartment, a top having a central opening and having equi-spaced struck-out portions near its circumference, valve means formed of resilient material and having curved arms in spaced relation thereto, and having parts 20 at their free ends to engage and seat within said struck-out portions of the top.
2. In a vanity case having a powder compartment, a top having a central opening and having a plurality of struck-out portions near its edge, valve means for said central opening having a plurality of equally spaced radial arms which latter have elongated arcuate portions concentric with the top and spaced from the periphery 25 thereof and projections on the free ends of the arms extending into said struck-out portions of the top and being bent into engagement therewith.

In testimony whereof I have signed my 30 name to this specification.

WINFRED T. PARKIN.
